UNITED STATES PATENT OFFICE

158,155

COVER FOR A VESSEL

Earl S. Tupper, Upton, Mass.

Application October 5, 1946, Serial No. 133,774

Term of patent 14 years

(Cl. D44—15)

To all whom it may concern:

Be it known that Earl S. Tupper, a citizen of the United States, residing at Upton, in the county of Worcester and State of Massachusetts, has invented a new, original, and ornamental Design for a Cover for a Vessel, of which the following is a specification, reference being had to the accompanying drawing, forming part thereof.

Fig. 1 is a top plan view of a cover for a vessel, showing my new design;

Fig. 2 is a side elevational view; and

Figs. 3 and 4 are vertical sectional views thereof taken along the lines 3—3 and 4—4, respectively of Fig. 1.

I claim:

The ornamental design for a cover for a vessel, as shown.

EARL S. TUPPER.
